(57) **CLAIM**

The ornamental design for a deep fryer, as shown and described.

DESCRIPTION

FIG. 1 is a perspective view of a deep fryer showing my new design;

FIG. 2 is a left side elevational view thereof;

FIG. 3 is a right side elevational view thereof;

FIG. 4 is a rear elevational view thereof; and,

FIG. 5 is a top plan view thereof.

The broken lines shown in the drawings are for illustrative purposes only and form no part of the claimed design.
